UNITED STATES PATENT OFFICE.

THOMAS J. SULLIVAN AND GEORGE J. HARRIS, OF MILWAUKEE, WISCONSIN;
SAID HARRIS ASSIGNOR TO JOHN H. STOUTHAMER, OF MILWAUKEE,
WISCONSIN.

PNEUMATIC RENOVATOR.

No. 845,275.

Specification of Letters Patent.

Patented Feb. 26, 1907.

Application filed November 26, 1904. Serial No. 234,303.

To all whom it may concern:

Be it known that we, THOMAS J. SULLIVAN and GEORGE J. HARRIS, residing in Milwaukee, in the county of Milwaukee and State of Wisconsin, have invented new and useful Improvements in Pneumatic Renovators, of which the following is a description, reference being had to the accompanying drawings, which are a part of this specification.

Our invention has relation to improvements in pneumatic renovators for abstracting dust from carpets, furniture, and the like and to convey it to a separator or collector or to any other point of discharge.

The primary object of the invention is to provide an improved construction of renovator of such character that the mechanism for producing a current of air is contained within the machine itself and is operated entirely by the movement of the machine over the article to be renovated.

With the above primary object and other incidental objects in view the invention consists of the devices and parts or their equivalents, as hereinafter set forth.

In the accompanying drawings, Figure 1 is a side elevation of the complete device, parts broken away, the bag 42 being in section. Fig. 2 is a fragment of the carriage, the axle being in section. Fig. 3 is a top view with the dust-receiving bag and the top of the carriage removed, and Fig. 4 is a horizontal section on the line 4-4 of Fig. 1 with part broken away.

Referring to the drawings, the numeral 5 indicates a carriage, which is preferably in the form of a casing or shell. The exterior air is free to enter the main chamber 6 of this carriage through an opening 7. Below the main chamber is a passage 8, which extends longitudinally for substantially the length of the carriage and communicates near one end with a transverse air-passage 9, which passage communicates with an exit-opening 10, formed in the bottom piece of the carriage, and which bottom piece is adapted to be slid over the article to be cleaned. The exit-opening 10 is preferably provided with downwardly-converging bordering walls. One of these walls (indicated by the numeral 11) may be formed by upturning the bottom piece at the exit-opening and bending said upturned portion in a divergent plane and

the other wall (indicated by the numeral 12) by a portion extending downwardly from the bottom piece of the passage 9 at the exit-opening and slanting the said downwardly-extending portion toward the wall 11. In this manner a contracted exit-opening is provided. One of these walls is preferably adjustable, so as to widen or narrow the exit-opening, and in the accompanying illustration we have shown the wall 12 as adjustable, the adjustment being provided by forming the said wall with a projecting flat extension 13, which is placed against the bottom piece of the passage 9 and is held adjustably thereto by means of screws 14 passing through elongated slots 15 in one of the members (said slots shown in the drawings as being provided in the bottom piece of the passage 9) and entering the other member.

A passage 16 for discharging the dust-laden air from the carriage is provided at one end of said casing and extends upwardly to and through the top of the carriage and is open at its upper end for the free discharge of said air. Near its opposite end the passage 16 extends around beneath the bottom of the passage 9 and terminates at an opening 17, formed in the bottom of the carriage, preferably at a point close to the bordering wall 12 of the exit-opening 10.

Within the carriage and conveniently located in inwardly-inclined positions are two series of bellows, one series being preferably located at the left-hand end of the carriage and the other series at the right-hand end of said carriage. Each of these bellows consists of the usual stationary or fixed board 18, (a single fixed board, as shown, may be provided for the several alined, bellows,) movable board 19, and the flexible leather portion 20, connecting the two boards. Oppositely-arranged pairs of these bellows are alternately collapsed and extended by means of a crank-carrying axle, in connection with links extending from the cranks, and connected at their outer ends to the movable boards of the bellows. The axle (indicated by the numeral 21) carries on its opposite ends the traction-wheels 22, preferably rubber-tired and which are adapted to travel over the article to be cleaned or renovated. These wheels being fast on the axle will of course communicate their rotation to said axle, and the rotation of the axle in turn, by

means of the crank-and-link connections with the bellows, will have the effect of alternately collapsing and extending oppositely-disposed bellows. The axle is provided with one crank for each pair of bellows, and inasmuch as there are three pair of bellows shown in the accompanying illustration the axle is consequently shown as provided with three of the cranks, the said 5 cranks extending from the axle in different directions. We of course do not intend to limit ourselves to a particular number of bellows or other mechanism for creating the pneumatic current, inasmuch as, for instance, 10 where the specific form of bellows is employed instead of three pair being used only one pair or two pair or more than three pair may be employed without departing from the spirit and scope of our invention. In 15 such case, of course, the cranks upon the axle and the links extending from said cranks and connected to the bellows should be arranged accordingly. One of the end cranks of the axle is indicated by the numeral 23, the other end crank by the numeral 24, and the intermediate crank by the numeral 25. The two links connecting the crank 23 with the opposite bellows relating thereto are indicated by the numerals 26 26, 20 the two links connecting the crank 24 with the opposite bellows relating thereto by the numerals 27 27, and the two links connecting the intermediate crank 25 with the opposite bellows relating thereto by the numerals 28 28. The inner ends of all of these links are 25 loosely fitted to the wrists or pins of the cranks by being provided with sleeves 29, which loosely surround said wrists or pins. The outer ends of the links are pivotally connected to the inner sides of the bellows, conveniently to lugs 30, projecting from the movable boards of the bellows. The fixed board of each bellows is provided with an inlet-opening 31 and with an outlet-opening 32. The inlet-opening is controlled by means of an inwardly-opening flap-valve 33, usually of thin leather, and the outlet-opening is controlled by a similar but outwardly-opening valve 34. The outlet-opening of 30 each bellows communicates with a downwardly-extending passage 35. The lower ends of the several passages 35 communicate, respectively, with passages 36 36, arranged at opposite ends and transversely of 35 the casing, and the passages 36 in turn communicate with opposite ends of the air-passage 8.

In order to provide for the flexible portion 20 of each bellows moving uniformly when 60 either collapsed or extended, opposite sides of said flexible portion have arranged thereagainst or adjacent thereto lazy-tongs 37 37, the outer ends of the levers constituting each lazy-tongs being pivotally secured to lugs 38 65 and 39, projecting, respectively, from the

fixed and movable pieces of the bellows. By this arrangement of course the movable piece of each bellows is compelled to move in a straight path toward or from the fixed piece when the bellows is either collapsed or extended, and consequently the accordion folds or plaits of the flexible portion of the bellows collapse together or are extended apart an equal distance throughout. In order to prevent the sides of the flexible portions of the 70 alined bellows from contacting or rubbing against each other in the extension or collapsing of said bellows, we prefer to arrange plates 40 between the opposed sides of the adjacent bellows. 80

The carriage is provided with a top piece 41, which is supported by means of ledges projecting inwardly from the opposite sides and ends of the carriage at the upper edges of said carriage. In the drawings a bag 42 is 85 shown as connected to the upper edge of the carriage, and into this bag the dust-laden air which passes through the discharge-passage 16 is received. The top of the carriage is preferably provided centrally with a dust 90 pocket or receptacle 43. The dust-laden air therefore discharges directly into the bag 42, and the heavy particles or the dust drops into the pocket 43, the surfaces of the top 41 leading to the pocket being on a gradual declination toward the pocket, so that the particles of dust which do not fall directly into the pocket may slide down these inclined surfaces and be thereby carried into said pocket. 95 The air which enters the bag and is thus 100 freed from the particles of dust is free to pass out of the interstices or small openings of the bag.

Frequently the article to be cleaned may have an irregular or uneven surface. In order to enable the carriage to be pushed as evenly as possible over such rough or uneven surfaces wherever encountered to thereby insure the rotation of the wheels and consequent rotation of the axle, we prefer to 105 mount the opposite ends of the axle 21 in plates 44 44. These plates are arranged against the outer sides of the side pieces of the carriage, and the axle passes through elongated slots 45 45 in said side pieces, its 110 outer ends having their bearings in circular openings in the said plates 44. The plates are movably fitted and guided beneath outstanding and inturned flanges 46 46, formed at the inner opposed edges of plates 47 47, 115 which plates are secured to the outer sides of the side pieces of the carriage. From this construction it will be seen that the plates are movable in the guideways provided therefor, and consequently the axle, which has its 120 bearings in said plates, has a limited movement to the extent permitted by the elongated slots 45. The wheels, therefore, in striking any raised or upward projection in the surface over which the carriage is pushed 125 130

will rise, or, on the other hand, in passing into any concavities or depressions will be permitted to lower, whereby irregularities in the surface of the article over which the carriage is pushed are compensated for.

The operation and manner of using our improved renovator will now be explained.

The carriage is pushed over the surface of the article to be cleaned by means of a handle 48, which at its inner end joins or is connected to a yoke 49, the arms of said yoke straddling the carriage and being connected at their ends to the sides of said carriage. As the carriage is pushed over the surface of the article to be cleaned the wheels 22 are necessarily rotated, and this rotation, as before explained, is communicated to the axle 21. The cranks on this axle, in connection with the links 26, 27, and 28, extending from the respective cranks and connecting with the movable board of the bellows, will cause an alternating collapsing and extending of the opposite bellows of a pair, as most clearly shown in Fig. 3. In this figure it will be seen that the left-hand bellows which is connected up to the crank 23 is collapsed, while the right-hand bellows connected to the same crank is extended; also that the left-hand bellows which is connected to the crank 24 is extended, while the right-hand bellows connected to the same crank is collapsed. At this position of the two cranks 23 and 24 the position of the intermediate crank 25 is such that both of the bellows connected to said crank 25 are extended to some extent. However, upon the further rotation of the intermediate crank 25 the bellows operated thereby will likewise be alternately collapsed and extended.

Upon the extending of any one of the bellows a vacuum is created therein, and this permits the air in the chamber 6 to rush into the interior space of the bellows through the inlet-opening 31, the force of the air-opening the flap-valve 33 controlling said opening 31 and closing flap-valve 34, which controls outlet-opening 32. When the bellows is subsequently collapsed, the compression of the air will close the flap-valve 33, and thereby prevent the escape of air through the inlet-opening. The flap-valve 34, however, will be opened and the compressed air forced through the outlet-opening 32, thence down the passage 35 into passage 36, thence into passage 8, thence into transverse passage 9, and through the opening 10 of said passage and into the carpet or other article to be cleaned. The air thus forced through the article to be renovated extracts from said article dust and dirt, and the dust-laden air rises and passes upwardly through the opening 17 into passage 16, thence out of the upper end of said passage into the bag 42. The dust and heavy particles fall into the dust-receptacle 43, while the air, freed from said

particles, escapes through the meshes of the bag.

It will be seen from the foregoing description that the entire mechanism is operated by the act of moving or pushing the carriage over the surface of the article to be cleaned—that is to say, the mechanism for creating the air-current and which is contained within the machine itself is actuated by the movement of the casing, so as to operate upon the air in such manner as to abstract dust and dirt from the article.

While in the accompanying drawings and in the foregoing description we have shown and described a specific form of bellows mechanism within the casing for accomplishing the object desired, yet we do not wish to be understood as restricting ourselves thereto, inasmuch as we deem any other form of mechanism capable of producing an air-current and operated by the pushing of the carriage over the article to be cleaned as within the spirit and scope of our invention.

What we claim as our invention is—

1. In a pneumatic renovator, the combination of a carriage having adjacent openings in its bottom, mechanism mounted on the carriage for creating an air-current, passages leading around the ends of the carriage from said current-creating mechanism to one of the openings in the bottom of the carriage, and a passage leading from the other of said openings around the end of the carriage to a point of discharge.

2. In a pneumatic renovator, the combination of a carriage having a flat bottom provided with transverse adjacent openings, the carriage being also provided with a longitudinal passage in its bottom leading to one of said openings and a passage leading from the other of said openings around the end of the carriage to a point of discharge, and means for creating an air-current mounted on the carriage and communicating with the said longitudinal passage in the bottom of the carriage.

3. In a pneumatic renovator, the combination of a carriage having adjacent openings in its bottom, having a passage leading from one of said openings, having a longitudinal passage leading to the other of the said openings, and a transverse passage communicating with the end of said longitudinal passage, a series of current-creating devices mounted on the carriage and communicating with the said transverse passage, and means for operating said devices.

4. In a pneumatic renovator, the combination of a carriage in the form of a hollow casting or shell provided with an air-chamber, the said chamber being in communication with the external air through an opening in the wall of the chamber, and said carriage, also having passages opening through the bottom thereof, one of said passages leading

- to a point of discharge, means carried by the carriage and supplied with air from the air-chamber of the carriage, said means adapted to produce a current of air, and to which 5 means the other passage leads and is adapted to receive therefrom a current of air, and means operated by the movement of the carriage for actuating the air-current-producing means, whereby a current of air is forced 10 through the passage which leads to said air-current-producing means, thence along said passage and through the bottom of the carriage, thence through the article over which the carriage passes, and thence through the 15 other passage and to a place of discharge.
5. In a pneumatic renovator, the combination of a carriage adapted to be moved over the article to be cleaned, mechanism mounted on said carriage for creating an air-current 20 abstracting the dust from the article to be cleaned, the top of the carriage being provided with a depression or pocket forming a dust-receptacle, a bag secured over said top

of the carriage, and means for conveying into the bag the dust-laden air abstracted from 25 the article to be cleaned.

6. In a pneumatic renovator, the combination of a carriage adapted to be moved over the article to be cleaned, and provided with means for creating an air-current and means 30 for directing said current against the article to be cleaned, an axle mounted in the carriage so as to have free vertical movement and carrying a traction-wheel adapted to bear on the article to be cleaned, and a connection between the axle and the current-creating means adapted, when the axle is rotated, to cause an actuation of said current-creating means.

In testimony whereof we affix our signatures in presence of two witnesses.
